UNITED STATES PATENT OFFICE.

VIKTOR J. KOPIKOVSKI, OF PHILADELPHIA, PENNSYLVANIA.

DESIGN FOR A JAR-OPENER.

49,613.

Specification for Design.

Patented Sept. 5, 1916.

Application filed July 19, 1916. Serial No. 110,233. Term of patent 7 years.

To all whom it may concern:

Be it known that I, VIKTOR J. KOPIKOVSKI, a subject of the Czar of Russia, residing at Philadelphia, in the county of Philadelphia and State of Pennsylvania, have invented a new, original, and ornamental Design for a Jar-Opener, of which the following is a specification, reference being had to the accompanying drawing, forming part thereof.

The figure is a view in perspective of a jar opener, showing my new design.

I claim:

The ornamental design for a jar opener, as shown.

VIKTOR J. KOPIKOVSKI.
